UNITED STATES PATENT OFFICE.

WILLIAM LOEFFLER, OF SHEBOYGAN, WISCONSIN.

CHAIR-IRON.

1,316,621.

Specification of Letters Patent. Patented Sept. 23, 1919.

Application filed May 16, 1918. Serial No. 284,899.

To all whom it may concern:

Be it known that I, WILLIAM LOEFFLER, a citizen of the United States, and resident of Sheboygan, Sheboygan county, Wisconsin, have invented new and useful Improvements in Chair-Irons, of which the following is a description, reference being had to the accompanying drawings, which are a part of this specification.

10 This invention has for its object to provide a chair iron which will permit the chair to turn in its swivel movements without affecting its adjustment as to height, but which upon operation of a suitable part will 15 be capable of vertical adjustment by reason of such swivel movements.

Another object of the invention is to perfect details of construction of a chair iron having these characteristics.

20 With the above and other objects in view the invention consists in the chair iron as herein claimed and all equivalents.

Referring to the accompanying drawings in which like characters of reference indicate the same parts in different views:

Figure 1 is a vertical sectional view of a chair iron constructed in accordance with this invention;

Fig. 2 is a plan view thereof;

30 Fig. 3 is a sectional plan view of the crab showing the cams; and,

Fig. 4 is a front view with the cam lever sectioned.

In these drawings 10 indicates the hub, 35 preferably with an extension 11 to lengthen the bore which is provided with screw threads 12. The chair spider 13 of usual construction is pivotally mounted on the ears 14 of the fork 15, known as a crab, on the upper end of a spindle 16. The usual 40 stop lugs 17 on the crab playing in slots 18 of the spider limit the tilting movements of the chair seat, while a compression spring 19 serves to hold the chair seat in its normal 45 position in the ordinary manner.

The spindle 16 is not provided with screw threads but bears at its lower end against a screw member 20 which is provided with screw threads meshing with the threads 12 of the bore of the hub. The screw member 20 takes the end thrust of spindle 16 to support the weight of the chair seat and its load. As the friction of the intermeshing 50 screw threads is greater than the friction of this end thrust bearing, turning or swivel 55 movements of the chair seat will have no ef-

fect on the screw member, which will remain in its position in the bore of the hub to maintain the chair seat at a predetermined height. An antifriction bearing such as a 60 washer 21 may be introduced between the screw member 20 and the end of the spindle.

A bolt 22 passes centrally through the spindle and the screw member with a head 65 23 on its upper end and a pair of jam nuts 24 threaded on its lower end. A cam lever 25 is loosely mounted on the bolt 22 and has oppositely positioned cam faces bearing on corresponding cam surfaces 26 on the crab. By swinging the cam lever 25 it may be 70 raised or lowered by the action of these cams for raising or lowering the bolt 22 and consequently clamping the screw member and spindle together or releasing them.

In the normal or lowermost position of 75 the cam lever 25 the bolt 22 exerts no clamping action and the chair seat is free to turn without varying its vertical adjustment. When it is desired to raise or lower the chair seat the cam lever 25 is swung to a position shown in dotted lines in Fig. 2 where its cam action causes the bolt 22 to clamp the screw member 20 to the spindle 16 and then by turning the seat the screw member is also compelled to turn and thread its way 80 to a new position in the hub where it will remain when the clamping lever is returned to its normal position to retain the seat at the height to which it is adjusted. The extension on the hub affords a long range of 85 adjustment for the screw member with ample lateral support for the spindle in the bore of the hub.

The chair iron of this invention is very simple in its construction and is strong and 90 durable and inexpensive to manufacture.

I desire it to be understood that this invention is not limited to any specific form or arrangement of parts except in so far as such limitations are specified in the 100 claims.

What I claim as new and desire to secure by Letters Patent is:

1. A chair iron, comprising an internally threaded hub member, a chair supporting 105 spindle rotatably mounted in the hub member without having threaded engagement therewith, a screw member threaded in the hub member with the spindle bearing thereon, and means passing through the spindle 110 for clamping the screw member and the spindle together for turning the screw mem-

ber in the hub member on the turning of the spindle.

2. A chair iron, comprising a hub member having a screw threaded bore, a screw member threaded in the hub member, a seat supporting spindle rotatably mounted in the bore of the hub member and bearing on the screw member, and cam means carried by the spindle for clamping the screw member and the spindle together.

3. A chair iron, comprising a hub member provided with a screw threaded bore, a seat supporting spindle journaled within the threaded bore of the hub member with- 15 out threaded engagement therewith, a screw member threaded in the bore of the hub member and forming an end thrust bearing for the spindle, a clamping bolt passing through the screw member and the spindle, 20 and means for tightening the clamping bolt for clamping the screw member to the spindle for compelling it to turn therewith.

4. A chair iron, comprising a hub member with a screw threaded bore, a screw member threaded therein, a seat supporting spindle journaled within the threaded bore of the hub member and having an end thrust bearing on the screw member, a bolt passing through the screw member and the 25 spindle, and a cam lever loosely mounted on

the bolt and engaging the head thereof and provided with cam surfaces coöperating with cam surfaces on the end of the spindle for clamping the screw member with the spindle.

5. A chair iron, comprising a hub member having an extension at its lower end with a screw threaded bore passing through it and its extension, a screw member threaded in the bore, a seat supporting spindle rotatably mounted in the bore with end thrust bearing on the screw member, and clamping means at the upper end of the spindle for clamping the screw member to the spindle. 40

6. A chair iron, comprising an internally threaded nut, a screw engaged in the threads of the nut, a tubular chair spindle journaled within the nut and resting on the screw, and means passing through the spindle for connecting the spindle with the screw to compel 45 the two to rotate together for adjusting the height of the spindle in the nut and thereby adjusting the height of the chair.

In testimony whereof I affix my signature in presence of two witnesses.

WILLIAM LOEFFLER.
